UNITED STATES PATENT OFFICE.

ANTON OCHSNER, OF NEW HAVEN, CONNECTICUT, ASSIGNOR OF ONE-HALF
TO ROBERT OCHSNER, OF SAME PLACE.

COACH-LATCH.

SPECIFICATION forming part of Letters Patent No. 660,822, dated October 30, 1900.

Application filed April 2, 1900. Serial No. 11,090. (No model.)

To all whom it may concern:

Be it known that I, ANTON OCHSNER, of New Haven, in the county of New Haven and State of Connecticut, have invented a new Improvement in Coach-Latches; and I do hereby declare the following, when taken in connection with the accompanying drawings and the letters of reference marked thereon, to be a full, clear, and exact description of the same, and which said drawings constitute part of this specification, and represent, in—

Figure 1, a view in inside elevation of a coach-latch constructed in accordance with my invention; Fig. 2, a view of the casing of the latch with the cover and the working parts of the latch removed; Fig. 3, a reverse plan view of the cover; Fig. 4, a sectional view of the latch on the line *a b* of Fig. 1; Fig. 5, an enlarged broken section showing manner of securing the cover to the casing.

My invention relates to an improvement in coach-latches, the object being to produce a simple, strong, and durable latch constructed with particular reference to securing the cover of the latch in place.

With these ends in view my invention consists in a coach-latch having certain details of construction, as will be hereinafter described, and pointed out in the claim.

In carrying out my invention as herein shown I form upon the inner face of the cast-metal L-shaped cover 2 three enlargements or bosses 3, 4, and 5, each of which is formed with a slightly-tapering socket 6.

These sockets receive in snug engagement the correspondingly-located internally-threaded hubs 7, 8, and 9, formed upon the inner face of the main plate or casing 10 of the latch structure. The outer face of the cover 2 is formed

with counterbores 11, arranged concentrically with and opening into the sockets 6, before mentioned, the sockets and counterbores being separated each from the other by means of a small beveled annular flange or shoulder

12, as clearly shown in Fig. 5. The cover is secured to the casing 10 by means of screws 13, passed down through the counterbores 11, and thence into the hubs 7, 8, and 9. My improved construction as above described prevents, as it will readily be understood, the cover from any lateral displacement, as any tendency to

such displacement is at once resisted by the engagement of the walls of the sockets 6 with the exterior walls of the hubs 7, 8, and 9, so that if the screws should work loose the cover 55 will be still held against lateral play. This is an important advantage, as I scarcely need to explain that coach-latches are subjected to very severe usage, whereby they are so racked that their parts work loose if every 60 precaution is not taken to resist racking strain. Of course I do not limit myself to using three enlargements containing sockets in conjunction with three threaded hubs, as the number and location of such socketed enlargements and hubs may be varied as desired.

As herein shown, the latch is provided with a handle-lever 14, secured in place by means of a screw-stud 15, and employed to operate 70 the heavy bolt 16, provided with a mainspring 17. The handle-lever itself is controlled by means of a spring 18 and a buffer, (not shown, but located in a socket 19, situated near the roll-back 20;) but my present invention is not 75 concerned with these details, which are shown and described in my prior patent granted August 4, 1885, No. 323,719.

I would have it understood that I do not limit myself to the exact construction herein 80 shown and described, but hold myself at liberty to make such changes as fairly fall within the spirit and scope of my invention.

I am aware that it is not broadly new, and I do not, therefore, broadly claim the provision of one member of a lock structure with a hub and the other member thereof with a socket for the reception of the said hub, whereby the two members are registered and kept in registration as well as secured together by a screw passing through the socket into the hub.

Having fully described my invention, what I claim as new, and desire to secure by Letters Patent, is—

In a coach-latch, the combination with a main plate or casing formed upon its flat inner face with a plurality of externally-tapered, internally-threaded hubs, of a cast-metal, L-shaped cover formed upon its inner face with a plurality of enlargements or bosses corresponding in number and location to the

said hubs, and each furnished with a tapering socket adapted to receive one of the said hubs, and the said cover being formed in its flat outer face with a plurality of counterbores corresponding in number and location to the enlargements or bosses located upon its inner face, and arranged concentrically with and opening into the said sockets from which they are separated by beveled annular shoulders, screws passing through the said counterbores in the outer face of the cover and into the said screw-threaded hubs, and having their heads engaged with the said beveled shoulders, a spring-actuated sliding bolt

having bearing upon the flat inner face of the main plate, and extending under the said cover, and a handle-lever extending between the said plate and the said cover, coacting with the said bolt, and projecting upward above the upper edge of the case. 15 20

In testimony whereof I have signed this specification in the presence of two subscribing witnesses.

ANTON OCHSNER.
